APPARATUS FOR TREATING YARN
PACKAGES WITH FLUIDS

Wayne A. Mulligan, Utica, and William Kernan,
New Hartford, N. Y., assignors to Skenandoa
Rayon Corporation, Utica, N. Y., a corporation
of Delaware

Application December 2, 1944, Serial No. 566,374

2 Claims. (CL 68—189)

1
Our present invention relates to the processing of yarn packages, particularly rayon yarn packages, by the cake finishing method as it is generally taught in United States patents to Gordon, Jr., No. 1,973,953, granted September 18, 1934, and Gordon, Jr., et al., No. 2,002,481, granted May 21, 1935.

In accordance with these patents, it has been customary, once the annular cake or package of yarn has been built up in the usual cake spinning process, first to cover this package with a knitted or other expansible fabric jacket or possibly merely to wind twine or string around the yarn package to prevent dislodgment of the yarn therein during the subsequent washing and liquid treating processes, so as to prevent possible interference by dislodgment or misplacing of the yarn with the subsequent unwinding operation. Such displacement of the yarn from its original position in the spun cake by the action of the processing liquid or liquids is a usual and undesired consequence. This is to a large extent if not completely overcome by placing cloth jackets around each cake or yarn package, the process of washing and otherwise liquid treating the yarn packages being then conducted with the yarn packages in suitable buckets or on trays or mandrels. The use of such a protective covering or jacket is quite expensive as it involves a considerable amount of extra handling, which increases the labor cost and time necessary for manufacturing the yarn. It has, therefore, been for some time considered desirable to find some way of avoiding this jacketing of the yarn cakes or packages.

We have found that a main cause of displacement of the thread layers is due to the suction or vacuum created when the treating liquid, which has been flowing through the yarn packages in a generally outward direction, is stopped and the liquid is allowed to drain from the interior of the yarn packages. It has, for example, been customary in practice not only to jacket the cakes individually as aforesaid, but also to place therein perforated protective inserts as tubes or collars, usually of rubber. This also involves additional labor costs and is time consuming in the manufacturing operation. We have found that the present invention tends to prevent the undesired effects of the vacuum, and to obviate the previous requirement for use of protective collars or inserts and the jacketing of the cakes.

A primary object of the present invention, therefore, is to provide an apparatus by which

2
the creation of a vacuum upon the draining of a treating liquid from the interior of a yarn package or stack of yarn packages may be substantially, if not wholly, prevented.

5 A further object of the present invention is the provision of simplified means for holding yarn packages in a stack, with or without jackets, in such manner that the yarn packages of the stack may be treated with liquid in accordance with the prior practice as set forth in the patents above referred to, the treating liquid being constrained to flow outwardly through the yarn of the packages during the treating operation.

10 15 A further object of the present invention is to provide various selectively usable and operative means for admitting air to the interior of the yarn packages upon the draining of the liquid therefrom, so as to prevent the creation of any substantial vacuum therein, specifically by providing various check valve devices which may not be per se new, but which are usable and useful in the particular relation in which we now propose to employ them. We have found that by the practical use of this invention in the commercial manufacture of rayon yarn, superior results are obtained in respect to those attainable in accordance with the prior art teachings.

15 20 25 Other and more specific objects of the present invention will become apparent from the following specification and appended claims, when taken in connection with the accompanying drawings in which:

25 30 35 Figure 1 is a fragmentary view, principally in central vertical section, showing a stack of yarn packages and the means by which they are held in position for the liquid treating operations and illustrating one form of our present invention associated therewith;

35 40 Fig. 2 is a similar view showing a modified form of the invention;

40 45 Fig. 3 is a similar view showing a further modification;

45 50 Fig. 4 is a fragmentary view on an enlarged scale, principally in plan and in part in horizontal section on the line 4—4 of Fig. 2, illustrating the air inlet means of a closure for a stack of yarn packages in accordance with the present invention; and

50 55 Figs. 5 and 6 are fragmentary views all substantially in central vertical section illustrating on an enlarged scale different types of check valve means for the introduction of air into the interior of a yarn package or stack of such yarn packages to prevent the creation of any substantial vacuum therein.

Referring first to Fig. 1, wherein there is illustrated a stack of rayon yarn packages in buckets in a position for the washing and bleaching or other liquid treating operations, we have chosen to show the application of our invention to apparatus substantially the same as that particularly disclosed in Fig. 7 of the Gordon, Jr., Patent No. 1,973,953 above referred to. The structure shown comprises a carrier including a base member 1 adapted to support a stack, here shown as four buckets, each generally indicated at 2. Each bucket is adapted to hold an annular rayon cake or yarn package 3. As shown, each bucket comprises a base member 4 and an annular, downwardly tapering side wall member 5, which may be secured to the base member 4 in any suitable manner. The upper portion of the side wall member 5 is formed as shown at 6 to provide a seat for the base member 4 of the next higher bucket. The side wall member 5 of each bucket is provided with a plurality of perforations 7. Each of the base members 4 has a central aperture 8 therein. Through these apertures 8, which are aligned when the buckets 2 are stacked as shown, extends a central tubular member 9, which is of a length corresponding to the height of the entire stack and which is provided with a plurality of holes or perforations 10. If desired, the tube 9 may be omitted. The uppermost bucket 2 of the stack has seated in the portion 6 thereof, a suitable closure 11, which is provided with a lug 12 pivoted at 13 to one arm 14 of a securing bracket. It will be understood that this bracket has at least two arms 14 as shown, which are preferably symmetrically arranged. The central portion of the bracket is formed as an annular hub 15 to receive therethrough a rod 16, which is secured as by threading at 17 to the base or carrier 1 and is provided with a suitable compressing means as a wing nut 18.

In this way the stack may be rigidly held in position by tightening the nut 18, thus moving the bracket 14-15 downwardly and applying a downward force on the closure 11. This force effective on the stack of buckets is carried by the sides and bottoms of the buckets and not to any substantial extent by the yarn packages therein, so as not to distort the yarn due to the securing of the parts in the relation shown in Fig. 1.

Also as shown in Fig. 1 each yarn package 3 is provided with a surrounding jacket 19, although this jacket may sometimes be omitted when the principles of our present invention are employed.

Means are provided at various points along the path of movement of the support 1 and the stack of yarn packages carried thereby for supplying to the interior of these stacks various treating liquides including wash water, bleach, etc., the details of which form no part of the present invention. As shown, such means comprises here a header 20 having a passage 21 therein through which a treating liquid may be supplied to the stack of yarn packages above described. For this purpose the base member 1 has an aperture 22 adapted to be in vertical alignment with the central portion of the annular space within the yarn packages and preferably concentric with the tubular member 9. Thus treating liquid will be admitted through the passage 21 and the aperture 22 to the interior of the tubular member 9 and passes thence through the holes or perforations 10 to the interior space of each of the annular yarn packages. This treating liquid

will be constrained to flow outwardly through the yarn packages by reason of the closure 11 at the upper end of the stack thereof, so that the liquid flows through the yarn and thence through the perforations 7 in the side wall members 5 of the buckets and then drains to a suitable place beneath that portion of the structure shown in Fig. 1.

Referring now to Fig. 2, we have shown in somewhat more diagrammatic form a modified structure corresponding generally in function and operation to that shown in Fig. 1. In this view, however, the base member generally indicated at 23 includes in its structure, means corresponding both to the base 1 and to the liquid header 20 with the passages therein. This member includes a liquid passage 24 communicating with an aperture 25 in the upper wall thereof, which is in vertical alignment with other passages or holes 26 through the several plate-like members or trays 27 by which the yarn packages 3 are respectively supported. In this form of the invention, however, the buckets 2 previously described, are omitted and instead the trays 27 are supported and separated from one another by spacer members 28, so that when pressure is applied by the wing nut 18 threaded on the upper end of the rod 16 in the manner previously described, this pressure will be initially received by an upper plate or closure member 29 and thence transmitted to the base member 23 through the several spacer members 28 and trays 27 rather than through the yarn packages. The operation will be substantially the same as that for Fig. 1 with the exception of certain details for preventing the creation of a vacuum herein-after to be described in respect to both forms.

In Fig. 3 we have shown a further embodiment of our invention, which is similar to many respects to those previously described and wherein the same reference characters are used to designate corresponding parts. Here, however, the yarn packages 3 are shown without the jackets 19 which are illustrated in Figs. 1 and 2. As shown in this figure, the yarn packages 3 are respectively supported upon annular plates or trays 30, each of which has a central hole 31 defined by a downwardly extending flange 32. Surrounding and positioned by the flanges 32 are short tubular spacing members 33, each of which is provided with a plurality of holes 34, through which the treating liquid introduced through the passage 24 and the holes 25 and 31 may flow to the interior of the annular yarn packages. The closure means and the means for holding the stack in a desired position are substantially the same as those described for Fig. 1 and are identified by similar reference characters.

As above stated, the principal object of our invention is to provide a process step and a means by which upon the cessation of the application of treating liquid to the interior of the one or more yarn packages being treated and upon the draining of the liquid from such interior of the annular yarn package or packages, the creation of any substantial vacuum will be prevented inside the yarn package, which vacuum in practice tends to disarrange the yarn in the cake or yarn package and hence tends to interfere with the proper unwinding thereof, which is done in a subsequent stage in the manufacture of yarn.

For this purpose we have shown various forms of our invention, the simplest of which is illustrated in Figs. 2 and 4. As shown, the member 75 29 which forms the upper closure for the stack

of yarn packages is provided with several holes 35, which may be of such size and number as may be found by experience to be desirable and which extend through the upper closure. During the supplying of liquid to the interior portion of the stack of yarn packages, some liquid will flow outwardly through these holes 35, but this amount of fluid thus lost from effective use is relatively small and depends, of course, upon the size of the holes 35 and may in certain cases not be so great as to introduce an undesired pumping cost for the liquid. It is understood, of course, that in the usual process, this liquid is re-circulated so that there is, in fact, no loss of the liquid itself and the pumping cost only is increased by the flow of a part of the liquid through the holes 35. If desired, and in order to prevent liquid from being forceably ejected upwardly from the stack of yarn packages to an undesired extent, there may be provided a stud 36 secured to the closure 29 in any suitable way as by a screw 37 and carrying at its upper end a shield 38 (Figs. 2 and 4).

We prefer, however, to provide some form of check valve associated with the hole or holes through the upper closure of the yarn package or stack of yarn packages shown in the several figures. A simple form of such check valve and the one which is presently preferred is that illustrated in Figs. 1, 3 and 5 and comprises a sheet of flexible material 39. In accordance with this form of our invention there may be provided a plurality of holes 35 as previously described, which holes are preferably arranged in symmetrical form about the center of the closure 11 and in an annular series. The material 39 may 35 be of a relatively thin sheet of rubber gasket material, although we do not intend to be specifically limited to any particular type of material for this use as other materials which will be appropriate for such use will occur to those skilled in the art. As shown, this sheet 39 is suitably attached as by a screw 40 to the underside of the closure 11 centrally of the group of holes 35 therethrough. During the supplying of liquid to the interior of the yarn package or packages 3, the sheet 39 will be forced by the dynamic action of the liquid to the position shown in full lines in Fig. 5. However, upon the cessation of admission of the treating liquid and upon and during the draining thereof, which might tend to cause the creation of vacuum within the yarn packages, such vacuum will be prevented by the movement of the sheet 39 to the dotted line position shown in Fig. 5. It will be understood that these holes are provided of such diameter and in such number as will serve adequately to prevent the creation of any substantial vacuum, these factors being easily ascertainable by those skilled in the art.

In Fig. 6 there is shown another embodiment of our invention, principally a different type of check valve means for closing the air admitting aperture of the cover plate. In this figure the cover plate or closure is somewhat different from that shown at 11 in previous figures and is indicated at 41, it being, however, supported in the same way as previously described as indicated by the use of similar reference characters 13 and 14 for corresponding parts. The cover plate 41 is provided with a passage 42 having a right angle 70 turn therein as indicated at 43 and communicating with the atmosphere above the cover plate and with the underside thereof. Suitably secured, in a manner not particularly illustrated, to the underside of the cover plate 41 is a mem-

ber 44 forming a valve seat 45 surrounding a passage 46 therethrough, which is aligned with the passage 42. Associated with this valve seat is a valve member generally indicated at 47 having a suitable gasket 48 for cooperation with the valve seat 45, the valve member 47 being pivoted at 49 to the member 44. The member 44 adjacent to the pivot 49 is formed as shown to provide a limited movement only for the valve 47 as indicated by comparison between the full and dotted line positions thereof shown in the drawing. Thus the valve 47 may move but a slight distance off its seat under the influence of gravity upon the draining of liquid from the interior of a stack of cakes to admit air through the passages 43, 42 and 46 to prevent the creation of any substantial vacuum. During the supplying of liquid to the interior of the yarn packages the valve 47 will be held closed on its seat by the force of the liquid effective on the underside thereof.

It will thus be seen that we have provided means by which air may be caused to flow into the interior space within one or more annular yarn packages during the draining of treating liquid therefrom to prevent the creation of any substantial vacuum therein, which might disarrange the yarn in said packages and thus tend to interfere with the subsequent unwinding thereof and/or cause other undesired effects upon the yarn. We have shown several means by which this air may be introduced or permitted to flow in to prevent the vacuum as aforesaid. Realizing that these are only some of the possible means by which these results may be attained, we do not wish to be limited except by the scope of the appended claims, which are to be construed validly as broadly as the state of the prior art permits.

What is claimed is:

1. Apparatus for treating annular yarn packages with liquids, comprising means for holding an annular yarn package in a predetermined position, means for admitting a treating liquid into the interior of said annular yarn package through one end portion thereof, closure means for the other end portion of the interior of said yarn package for substantially confining the liquid against moving out said other end, the last named means being so constructed and arranged that the liquid supplied to the interior of the yarn package is constrained to flow outwardly therethrough, an aperture through said closure means, check valve means cooperating with said aperture for substantially preventing outflow of liquid through said aperture during the application of liquid for treating said yarn package as aforesaid, said check valve means comprising a sheet of flexible material disposed beneath and adjacent to said closure and adapted upon and during the supplying of liquid to the interior of said yarn package to be forced by the liquid to cover and close said hole, and to flex to open a passage from said hole to the interior of said yarn package upon and during the draining of the liquid from said interior to admit air from the atmosphere to prevent the creation of any substantial vacuum within said yarn package, and thereby to prevent any disarrangement of the yarn of said package which might tend to interfere with the subsequent unwinding thereof.

2. Apparatus for treating annular yarn packages with liquids, comprising means for holding an annular yarn package in a predetermined position, means for admitting a treating liquid into the interior of said annular yarn package through one end portion thereof, closure means for the

other end portion of the interior of said yarn package for substantially confining the liquid against moving out said other end, the last named means being so constructed and arranged that the liquid supplied to the interior of the yarn package is constrained to flow outwardly there-through, a plurality of holes through said closure means symmetrically disposed about the center thereof in a substantially annular series, a sheet of flexible material secured to the underside of said closure means centrally thereof and of such size as to cover all said holes, said sheet of flexible material being so constructed and arranged that upon and during the admission of liquid into the interior of said yarn package, said sheet will be caused to cover and prevent substantial egress of liquid through said holes, and upon and during the draining of said liquid from the interior of said yarn package, said sheet material will be caused to move away from said holes to permit

inflow of air therethrough, to prevent the creation of any substantial vacuum within said yarn package, and thereby to prevent any disarrangement of the yarn of said package which might tend to interfere with the subsequent unwinding thereof.

WAYNE A. MULLIGAN.
WILLIAM KERNAN.
